UNITED STATES PATENT OFFICE.

JOSEF KOVARIK, OF CORVALLIS, OREGON.

RAIL JOINT.

Application filed August 20, 1925. Serial No. 51,430.

To all whom it may concern:

Be it known that I, JOSEF KOVARIK, a citizen of the United States, residing at Corvallis, in the county of Benton and State of Oregon, have invented certain new and useful Improvements in Rail Joints, of which the following is a specification.

This invention relates to new and useful improvements in rail joints.

10 The primary object of the invention is to provide an improved form of joint for rail ends by means of which the usual fish plate connectors may be dispensed with.

15 Other objects and advantages of the invention will be apparent during the course of the following description.

20 In the accompanying drawing forming a part of this specification and in which like numerals are employed to designate like parts throughout the same.

Figure 1 is a side elevational view of a pair of rail ends which are joined by the improved means embodying this invention,

25 Figure 2 is a top plan view of the structure shown in Fig. 1,

Figure 3 is a similar view to Fig. 1, partly shown in section, of an improved form of rail joint embodying this invention,

30 Figure 4 is a longitudinal sectional view of one of the rail ends, taken upon lines JV-IV of Fig. 3, and

Fig. 5 is a vertical sectional view of the second rail end shown in Fig. 3 and taken upon lines V-V of this latter figure.

35 In the drawing, wherein for the purpose of illustration is shown a preferred embodiment of this invention, the numerals 5 and 6 designate the joined rail ends which include tread portions 7 and 8 respectively.

40 In Figs. 1 and 2 the adjacent end portions of the treads 7 and 8 are illustrated as having formed therein grooves 9 and 10 which extend longitudinally of the rail ends and are of dove-tail-shape in cross-section and 45 open thru the top faces of the treads 7 and 8. Positioned within these grooves 9 and 10 and conforming in cross-sectional shape therewith is a key 11 which is intended to prevent relative lateral movement of either 50 of the rail ends 5 or 6 in respect to the remaining end.

In Figs. 3 to 5 inclusive the rail ends 5 and 6 are illustrated as having formed there-

in the longitudinally extending pockets 12 and 13 which are formed primarily in the 55 web portion of the rail ends and communicate with the grooves 9 and 10. These pockets 12 and 13 have pivotally mounted therein the dogs 14 and 15 which have their free ends pressed upwardly by the leaf 60 springs 16 and 17. The under face of the key 11 is formed with notches 18 and 19, adjacent the end portions of the key, for receiving the upper ends of the dogs 15 and 16.

To permit these rail ends to be disconnected, transverse openings 20 and 21 are formed therein and through which the pin 22 may be inserted for permitting it to bear against the upper edge of a dog for forcing the latter downwardly against its 70 spring to remove the end of the dog from the key notch in which it is intended to be seated. Figs. 3 and 4 show the transverse openings 20 and 21 as being formed with beveled end faces 23 which function to guide 75 the pin 22 into a proper position for engaging a dog.

It is to be understood that the forms of this invention herewith shown and described are to be taken as preferred examples 80 of the same, and that various changes in the shape, size, and arrangement of parts may be resorted to without departing from the spirit of the invention or the scope of the subjoined claims.

Having thus described the invention, I 85 claim:—

1. In a rail joint, a pair of rail ends having longitudinally extending grooves formed in their tread portions with each groove of dove-tail-shape in cross-section and opening through the end face of the rail end, a key of dove-tail-shape in cross-section received in the grooves formed in said rail ends, said key having notches formed in its 90 lower face, and upwardly spring pressed dogs carried by said rail ends and adapted to have their ends received in the notches formed in said key for preventing relative longitudinal movement between the rail ends 95 and the key.

2. In a rail joint, a pair of rail ends having longitudinally extending grooves formed in their tread portions with each groove of dove-tail-shape in cross-section 100 and opening through the end face of

the rail end, a key of dove-tail-shape in cross-section received in the grooves formed in said rail ends, said key having notches formed in its lower face, said rail ends having pockets formed in their web portions which communicate with the grooves, a pivoted dog in each pocket adapted to have its

free end enter a notch in said key, and a spring in each pocket below its respective dog for holding the latter in its notch entering position. 10

In testimony whereof I affix my signature.

JOSEF KOVARIK.
